UNITED STATES PATENT OFFICE.

ISAIAH J. ALLEN, OF PORTLAND, OREGON.

RULE.

1,368,876.

Specification of Letters Patent. Patented Feb. 15, 1921.

Application filed July 19, 1919, Serial No. 311,903. Renewed July 12, 1920. Serial No. 395,763.

To all whom it may concern:

Be it known that I, ISAIAH J. ALLEN, a citizen of the United States, residing at Portland, in the county of Multnomah and 5 State of Oregon, have invented new and useful Improvements in Rules, of which the following is a specification.

This invention has reference to a combination rule and roofing tool, and has for its 10 primary object to produce a device of this character which, in addition to employment as an ordinary rule provides means whereby the lengths, bevels and other cuts relative to the framing of a roof may be accurately 15 ascertained in an easy manner.

Other objects and advantages will present themselves as the nature of the invention is better understood, reference being had to the accompanying drawings, in which:

20 Figure 1 is a perspective view of the improvement complete, the elements constituting the same being folded.

Fig. 2 is an edge view thereof, the folding or hinged member being extended.

25 Fig. 3 is a view looking toward the back of the rule proper, the slidable member or blade being removed.

Fig. 4 is an elevation showing the slidable member adjusted longitudinally on the rule 30 proper.

Fig. 5 is an inner face view of the sliding member or blade.

Fig. 6 is a sectional view approximately 35 on the line 6—6 of Fig. 2.

Fig. 7 is a detail view showing the arrangement of the blade arranged at an angle with respect to the main member or rule proper.

Fig. 8 is a diagram illustrating a portion 40 of a building in order to demonstrate the uses of the improvement.

As disclosed by the drawings, my improvement contemplates the employment of a rule proper which is designated by the 45 numeral 10. The element 10 will herein-after for convenience be referred to as the main member of the device. The main member 10 for the major portion of its length is centrally provided with a slot 11 and has, at one of its ends a metallic reinforcing plate or band 12 which, upon one of its faces is slotted longitudinally and transversely, and the metal bounded by the slits bent outwardly to provide angle guide lugs 50 55 13. The rule, at its opposite end has hingedly connected thereto, as at 14 a leg 15

which is of a width less than one-half of the width of the main member 10. The leg 15, at its outer end, and upon one of its faces is provided with an outstanding lug 16, and 60 upon its opposite face with a button member 17 that is designed to be received in a socket 18 in the face of the member 10 whereby the leg is folded and held against the face of the member 10. The main member 10, upon the 65 side thereof provided with the lugs 13, but at the opposite end from that upon which the lugs are arranged is formed with an outstanding stop element 19. The slidable member or blade is indicated by the numeral 70 20. This member, upon its inner face, and inward of its edges is formed with longitudinally extending slots 21. These slots are cut at an oblique angle to each other and are designed to receive therein guide lugs 13. 75 The member or blade 20 has one of its ends 22 that is designed to receive the stop 19 when the blade 20 is disposed to fully cover one of the faces of the main member 10. The member or blade 20, adjacent to the end 80 thereof provided with the notch 22 has secured thereon a laterally extending threaded stud 23 that passes through the slot 11 in the main member 10, and this threaded element 23 is engaged by a milled nut 24.

The blade 20, on its opposite faces, and adjacent its edges is divided into inches and fractions thereof. The blade, upon the inner face thereof has additional divisions thereon to indicate lengths for common rafters, indicated by the numerals 25 and hip and valley rafters which are indicated by the numerals 26. The leg 15 upon its outer, and if desired upon its inner face has divisions of inches and fractions thereof which 95 form a continuation of the inches and subdivisions thereof inscribed upon the outer face of the main member 10, the said main member having both its edges upon its said outer face so inscribed. The inner face of 100 the member 10 is provided with angle lines indicating the hip cuts for roof boards, indicated by the numerals 27, bevel cuts for jack rafters indicated by the numerals 28, hip and valley bevels indicated by the numerals 105 29, common rafter ridge cuts indicated by the numerals 31, base cuts indicated by the numerals 32, hip and valley ridge cuts and base cuts indicated by the numerals 34 and 35 respectively. In addition to this, the 110 main member, besides the bevel inscriptions indicating the hip cuts for roof boards, bevel

cuts for jack rafters and hip and bevel rafters is provided with angle marks 50 indicating miter cuts and a straight mark 51 intersecting said angle marks.

- 5 We will now refer to the diagram illustrated in Fig. 8 of the drawings. It will be noted that the dimensions are inscribed on the building. It will be seen that the building is to have a gable and a hip roof.
- 10 To get the length of the common rafters, we loosen the thumb screw and push the sliding member or blade forward until 9 on the upper middle space is even with the end of the main member, then tighten the screw,
- 15 and on the timber that is to be used for the rafter measure off 12 lengths of the rule as extended. This will give the exact length of the common rafter. If it is desired to know the length of the rafter without
- 20 measuring on the timber it will be found by adding the standard 12 inches on the upper edge of the main member to the figures exposed on the upper edge of the sliding member or blade. In this instance the number
- 25 reached is 3, and adding 12 and 3 we have 15, which is the length of the rafter. To get the length of the hip or valley rafter the sliding member is moved on the main mem-
- 30 ber until 9 in the lower middle space is even with the end of the main member. The leg 15 is then unfolded, and the measurements are obtained for a hip rafter. The length of the hip or valley rafters may be known by adding the length of the leg and the figures
- 35 exposed on the upper edge of the sliding member to the standard 12 inches on the upper edge of the main member. It is to be noted that the lower edge of the rule when the leg is extended is practically 17 inches
- 40 long and I have divided these 17 inches into 12 equal parts to be used more especially in making measurements on angles of 45 degrees and on hip and valley rafters. This obviates the use of troublesome fractions.
- 45 To get the cut of the rafters, loosen the nut until the sliding member drops below the stop. Move the slide back until it is released from the guide lugs 13. Then with the screw 23 for a pivot revolve the blade
- 50 or sliding member angularly across the main member. Set the edge of the blade as at 9, the figure representing the rise or pitch of the rafter. The base cut is found by setting the sliding member or blade on
- 55 the line of the main member which squares with the one which represents the rise of the rafter. The bevels for top of jack rafters and the bevels for hip and valley rafters and also the miters and the square cuts are all
- 60 found in the same manner, always using the

number or figure representing the rise of the rule with the exception, of course, of the miter and square lines which are not numbered. It will be noted that I have used a 12 inch run and 9 inch rise for illustrating, 65 the reason being that in this example the common rafter is an even 15'. When the base is more or less than 12' reduce the rise in feet to inches, and divide by base in feet, and this will give the rise per foot of base. 70 For example, base 16', rise 8', $8' \times 12'' = 96$, divided $\times 16'$ gives 6'', which is the angle per foot of base. The end of main member 10 is then set to 6 on the upper middle space of slide member 20. The screw is then tight- 75 ened and we have the length of one foot. Then measure off 16 lengths of the rule as extended and we will have the length of a rafter for a 16' base and 8' rise. It is to be noted that the hypotenuse may be found 80 when the base and vertical are given and the base may be found when the hypotenuse and vertical are given, and it is thought, from the foregoing description that the construction and use of the improvement will be perfectly apparent. 85

Having thus described the invention, what is claimed as new is:—

1. In a device for the purpose set forth, a main member having a slot for the major portion of its length, and said main member being graduated to provide inches and fractions thereof, and angle lines to indicate bevels, a graduated leg on one end of the main member pivoted thereto and designed 90 to be swung against the main member or parallel therewith, latching means for the leg when in its former position, a slide member on the main member, a binding element passing through the slot for sustaining 95 the sliding member on the main member, guide means for the sliding member, stop means therefor, and said binding means designed to serve as a pivot whereby the sliding member may be swung angularly with 100 respect to the main member.

2. In a device for the purpose set forth, a main graduated member, a stop at one end thereof, guide lugs adjacent the other end thereof, a sliding member receiving the 110 guide lugs and having a notch to engage with the stop when the sliding member is in one position with respect to the main member, binding means between the main member and the sliding member, and said binding means designed to serve as a pivot to permit of the sliding member being swung 115 angularly over the main member.

In testimony whereof I affix my signature.
ISAIAH J. ALLEN.
